CLAIM

The ornamental design for an automobile headlight lens, as shown and described.

DESCRIPTION

FIG. 1 is a perspective view of an automobile headlight lens; FIG. 2 is a front view thereof;

FIG. 3 is a right side view thereof; and,

FIG. 4 is a top view thereof.

The broken lines are included to show environmental structure and form no part of the claimed design. The drawings and descriptions represent the right side embodiment. The claim is also for a mirror image left side embodiment.
